DRIVING MEANS FOR TAXIMETERS

Filed July 20, 1925

FIG. 1.

INVENTORS.
Charles Anstotz
BY Waldemar Sique
Hastings W. Baker,
ATTORNEY

UNITED STATES PATENT OFFICE.

CHARLES ANSTOTZ AND WALDEMAR SAUPE, OF NEW YORK, N. Y., ASSIGNEES TO OHMER FARE REGISTER COMPANY, OF DAYTON, OHIO, A CORPORATION OF NEW YORK.

DRIVING MEANS FOR TAXIMETERS.

Application filed July 20, 1925. Serial No. 44,758.

This invention relates to a combined indicating and registering apparatus for taximeters, and consists of an improvement on the structure shown in the patent to Popp 5 and De Horevitz, 912,728 granted February 16, 1909.

One of the objects of this invention is to remedy such defects so that the drive for the taximeter will be accurate and reliable.

- 10 The invention further provides an apparatus of the character referred to which shall be comparatively simple in its construction, strong, durable, efficient in its operation, readily interchangeable with the 15 mechanism now in use and comparatively inexpensive to manufacture. The objectionable levers above referred to are eliminated so that there is no chance for the counters to be driven incorrectly thereby. 20 With the foregoing and other objects in view, the invention consists of the novel construction, combination and arrangement of parts hereinafter more specifically described and illustrated in the accompanying drawing 25 wherein is shown the preferred embodiment of the invention, but it is to be understood that changes, variations and modifications can be resorted to which come within the scope of the claims hereunto appended.

30 In the drawings:

Figure 1 is a side elevation of the taximeter having incorporated therein the improvement which constitutes one embodiment of this invention.

35 Referring to the drawing in detail, the side wall of the casing is denoted by the reference character 10. Journaled in this side wall is a shaft 11, on which is mounted a gear 12, driven by a worm 13, carried 40 by a short shaft 14, journaled in bearings 15 and 16, which bearings are secured to the side wall 10. A pitman 17 is actuated by the gear 12, which pitman in turn actuates a counter (not shown) which counter indicates the total number of units of distance 45 traveled.

A shaft 18 is operatively connected with the shaft 14 by means of a resilient or flexible connection 19, which in the specific instance shown is a spring, the lower end of 50 which fits into the bifurcated upper end 20 of the shaft 18 and the upper end of the flexible connection 19 fits into the bifurcated lower extremity of the shaft 14. The shaft

18 is journaled in bearings 21 and 22. The bearing 21 is provided with a slot 23, through which extends a pin 24, the said pin 24 extending into the side wall 10. A stop 25 is mounted on the side wall 10 which limits the inward movement of the bearing 21. A spring 26 tends to pull the slideable bearing 21 inwardly so that a worm 27, secured to the shaft 18 immediately above the bearing 21, is brought into mesh with a gear 28 secured to the main driving shaft 65 A of the taximeter. The position of the parts shown in Figure 1 is the position the parts would be in when the flag (not shown) was in operative position. When however the flag is rotated to the vacant position, 70 the cam 29 on the flag shaft 30 engages the upper end of the shaft 18 and moves it outwardly from the flag shaft 30 so that the worm 27 is disengaged from the gear 28.

The flexible shaft (not shown) is driven by the front wheels of the automobile or other moving part thereof and is connected with a spindle 31, journaled in a bearing 32, carried by the side wall of the taximeter, 80 which spindle 31 is provided with a disc 33, carrying a pawl 34. The shaft 35 is journaled in a bearing 36, which shaft is provided at its lower end with a ratchet wheel 37, which is operated by the pawl 34, which pawl is pressed against the teeth of the ratchet wheel by means of a spring 38. The shaft 35 carries at its upper end a pinion 39, which meshes with and drives a pinion 40 secured to the lower end of the shaft 18.

The gear 12 is provided with a pin 41, 90 adapted to engage a lug 42 on a bar 43, which bar is mounted on a pin 44, on a crank 45 which operates the counter indicating the number of units of paid distance and on a pin 46 on the bell crank lever 47. When the flag shaft 30 is in hired position, as indicated in the drawing, the pin 41 which rotates in an anti-clockwise direction engages the lug 42 and moves the bar 43 to the right, the bar sliding on the pin 46 and actuating the crank arm 45. When however the flag shaft is rotating to the vacant position the end 48 of the bell crank lever 47 enters the cam 49 of the flag shaft 30 thereby permitting the spring 50 to rotate the bell crank lever 47 clockwise on its fulcrum 51 so that the end of the slot 52 of the bar 43 engages the pin 46 so that the bar is moved to the 100 105

right and the lug 42 is moved so that the pin 41 cannot actuate the said bar. Under these conditions the counter which indicates the total number of units of distance will be driven when the machine is operated by means of the pitman 17, and while the pin 41 is rotated, it does not actuate the bar 43 and hence the counter for the units of paid distance is not actuated nor is the main shaft of the taximeter driven under these conditions for the cam 29 has disengaged the worm 27 from the main shaft driving gear 28.

Without further description it is thought that the features and advantages of the invention will be readily apparent to those skilled in the art and it will be understood that changes in the form, proportion and details of construction may be resorted to without departing from the spirit of the invention and scope of the appended claims.

We claim:

1. A driving means for a taximeter, including a rotatable spindle adapted to be driven by a moving part of a vehicle, a pinion thereon, a driving shaft, bearings for said driving shaft, including a substantially stationary bearing near the lower end of the said shaft and a slideable bearing positioned above the substantially stationary bearing, a main operating shaft, a gear thereon, a worm on the said driving shaft whereby said gear is driven, a pinion on the lower end of said driving shaft adapted to mesh with said first mentioned pinion, said slideable bearing permitting said worm to be brought into or out of driving contact with said gear, and means whereby said slideable bearing is tensioned so as to tend to hold said worm in mesh with said gear.
2. A driving means for a taximeter including a driving shaft, a second shaft driven thereby, a flexible connection between said shafts, means driven by said second shaft, a main operating shaft, means whereby said main operating shaft may be driven by said driving shaft and means whereby said last mentioned means is rendered inoperative.
3. A driving means for a taximeter, including a driving shaft, a bearing near one end of said shaft permitting a slight axial movement of said shaft, a slideable bearing for said shaft provided with a slot therein, means passing through said slot and into the side of the taximeter so as to permit of a greater movement of the upper end of said

shaft than the movement of the lower end, a main operating shaft for the taximeter, means whereby said shafts may be operatively connected so that the said main operating shaft will be driven by the driving shaft when the slideable bearing is in one position, and so that the said last mentioned means will be rendered inoperative when the slideable bearing is in another of its positions.

4. A driving means for taximeters including a driving shaft, a main operating shaft, means whereby said shafts may be operatively connected, a flag shaft and means carried by said flag shaft directly engaging said driving shaft whereby the first mentioned means may be rendered inoperative.

5. A driving means for taximeters, including a driving shaft, a second shaft driven thereby, a flexible connection between said shafts, elements driven by each of said shafts and a cam whereby the driving shaft is rendered inoperative in so far as the element driven thereby is concerned.

6. A driving means for taximeters including a driving shaft, a slideable bearing therefor, a worm carried by said shaft, a main operating gear driven thereby, a flag shaft, a cam thereon adapted to engage said driving shaft and move said worm out of mesh with said gear when the flag shaft is in vacant position and spring means to cause said gear and worm to mesh when the flag shaft is in hired position.

7. A driving means for taximeters including a driving shaft, a bearing near one end of said shaft, a slideable bearing intermediate the ends of said shaft, a second shaft, a flexible connection between said driving shaft and said second shaft, means driven by said second shaft whereby the total number of units of distance are recorded, a worm on said driving shaft, a main driving gear driven thereby, a flag shaft positioned near the upper end of said driving shaft, a cam carried thereby said cam engaging the upper end of said driving shaft and slightly rotating it on the first mentioned bearing, as a fulcrum causing the worm to be unmeshed from said main operating gear and means whereby said worm is caused to mesh with said main operating gear when the flag shaft has been rotated to hired position.

In testimony whereof we affix our signatures.

CHARLES ANSTOTZ.
WALDEMAR SAUPE.
